United States Patent Office

Des. 232,046
Patented July 9, 1974

232,046

TOY COW

Ralph W. Crawford, East Aurora, N.Y., assignor to The Quaker Oats Company, Chicago, Ill.

Filed Jan. 2, 1973, Ser. No. 320,296

Term of patent 14 years

Int. Cl. D21—01
U.S. Cl. D34—15 D

FIG. 1

FIG. 2

FIG. 3

FIG. 4

FIG. 1 is a right front perspective view of a toy cow showing my new design;

FIG. 2 is a left front perspective view thereof;

FIG. 3 is a rear elevational view thereof; and

FIG. 4 is a top plan view thereof.

I claim:

The ornamental design for a toy cow, substantially as shown.
